CLAIM

The ornamental design for a finger-mounted gunsight toy, as shown and described.

DESCRIPTION

FIG. 1 is a right side perspective view of a finger-mounted gunsight toy showing our new design, the left side perspective view being a mirror image and the broken line showing of the hand is for illustrative purposes only, forming no part of the claimed design;

FIG. 2 is a top view thereof;

FIG. 3 is a bottom view thereof;

FIG. 4 is a rear elevation thereof; and,

FIG. 5 is a front elevation thereof.
